UNITED STATES PATENT OFFICE

JOHN SELBY-HELE, OF SANTA MONICA, CALIFORNIA

DESIGN FOR A SEWING CABINET

Application filed November 2, 1932. Serial No. 45,706. Term of patent 3½ years.

To all whom it may concern:

Be it known that I, JOHN SELBY-HELE, a citizen of the United States, residing at Santa Monica, in the county of Los Angeles and State of California, have invented a new, original, and ornamental Design for a Sewing Cabinet, of which the following is a specification, reference being had to the accompanying drawing, forming part thereof.

Fig. 1 is a perspective view of a sewing cabinet showing my new design.

Fig. 2 is a top plan view of the same.

I claim:

The ornamental design for a sewing cabinet, as shown.

J. SELBY-HELE.
